(57) **CLAIM**

The ornamental design for an image projector, as shown and described.

DESCRIPTION

FIG. 1 is a top, rear, right side perspective view of the image projector;

FIG. 2 is a bottom, rear, right side perspective view of the image projector shown in FIG. 1;

FIG. 3 is a front view of the image projector shown in FIG. 1;

FIG. 4 is a rear view of the image projector shown in FIG. 1;

FIG. 5 is a left-side view of the image projector shown in FIG. 1;

FIG. 6 is a right-side view of the image projector shown in FIG. 1;

FIG. 7 is a top view of the image projector shown in FIG. 1; and,

FIG. 8 is a bottom view of the image projector shown in FIG. 1.

The broken lines in the drawings depict portions of the image projector and form no part of the claimed design.
